(57) CLAIM

The ornamental design for the pumpless inflation device for inflating ball, as shown and described.

DESCRIPTION

FIG. 1 is an overall view of my portable inflation device;

FIG. 2 is a fragmentary view illustrating one side of the part of my inflation device concerned with engaging the valve stem of a tire;

FIG. 3 is a fragmentary view of the other side of the stem-engaging part of my inflation device; and,

FIG. 4 is a view of the backside of my inflation device, with a slight curvature being utilized to indicate the flexibility of the elongate part of my novel design.
